PROTECTIVE CASING FOR SAFES.

1,410,808.

Specification of Letters Patent. Patented Mar. 28, 1922.

Application filed March 23, 1921. Serial No. 454,927.

(GRANTED UNDER THE PROVISIONS OF THE ACT OF MARCH 3, 1921, 41 STAT. L., 1313.)

To all whom it may concern:

Be it known that I, ROBERT HOMOLLE, a citizen of the Republic of France, and resident of Paris, 20 Rue Guyot, France, have 5 invented certain new and useful Improvements in Protective Casings for Safes, (for which I have filed an application in France, on February 20, 1919, Patent No. 496,030,) of which the following is a specification.

10 This invention has for its object to provide a safe of any type with a protective casing, made of smoke producing materials, the construction of the casing being such that it can be applied not only to safes but also to 15 strong-doors and even to the walls of strong-rooms of banks.

The accompanying drawing illustrates, by way of example, how the protective casing or shield is to be applied to a safe.

20 The casing *a*, which is composed of smoke producing materials, is preferably set directly next to the outer steel casing *b*.

In the case of a vault door, the smoke generating materials will be arranged against 25 the outer wall of the door.

When the safe or the like structure is attacked by means of a blow pipe, as soon as the flame penetrates the outer steel casing *b* it ignites the smoke-producing materials, 30 and the latter immediately generate a thick smoke which escapes through the hole bored by the blow pipe.

Since this smoke cannot be concealed it not only constitutes an excellent means for attracting the attention of the attendants, but 35 also, because of its density and asphyxiating property, it tends to prevent the safe-blower from continuing his work and compels him to leave the spot where he was working.

It is to be understood that the device may 40 of course be composed of any appropriate smoke producing materials, in particular when the latter contain coal and hydro-carbon.

I claim as my invention:—

A protective casing for safes, strong-doors and the like, comprising an outer metal case, and a wall or layer of material for producing a dense smoke arranged directly against the inner surface of said case, so that when 50 the latter is penetrated by the flame of a blow pipe, such flame will immediately ignite said material, and the smoke generated thereby will escape through the hole cut by the blow pipe and form a thick smoke screen 55 which will obscure the portion of the safe on which the safe-blower is operating and thus prevent him from continuing his work, and which will also serve to warn the attendants.

In testimony whereof I have signed this 60 specification.

ROBERT HOMOLLE.
